UNITED STATES PATENT OFFICE.

PAUL E. NORRIS, OF WILKINSBURG, PENNSYLVANIA.

DESIGN FOR A BATTERY-PLATE-SUPPORTING TRAY.

56,676.

Specification for Design. Patented Nov. 23, 1920.

Application filed August 16, 1920. Serial No. 403,957. Term of patent 14 years.

To all whom it may concern:

Be it known that I, PAUL E. NORRIS, a citizen of the United States, residing at Wilkinsburg, in the county of Allegheny and State of Pennsylvania, have invented a new, original, and ornamental Design for a Battery-Plate-Supporting Tray, of which the following is a specification, reference being had to the accompanying drawing, forming part thereof.

In the drawing:

The figure is a top plan view of the tray.
I claim:

The ornamental design for a battery plate supporting tray, as shown.

PAUL E. NORRIS.
